UNITED STATES PATENT OFFICE.

IRL L. PENSE, OF BONESTEEL, SOUTH DAKOTA.

HORSE-DETACHER.

1,216,601.

Specification of Letters Patent. Patented Feb. 20, 1917.

Application filed May 13, 1916. Serial No. 97,355.

To all whom it may concern:

Be it known that I, IRL L. PENSE, a citizen of the United States, residing at Bone-steel, in the county of Gregory and State 5 of South Dakota, have invented certain new and useful Improvements in Horse-Detachers, of which the following is a specification, reference being had to the accompanying drawings.

10 This invention relates to means for detaching horses from vehicles, and particularly to a horse detacher specially designed to be used with a team of horses connected to the tongue of a wagon by the usual draft 15 device consisting of an evener bar and single trees.

The general object of the invention is to provide a very simple construction which may be manually operated to release the 20 connection between the tongue and the evener bar, and which may be applied to the tongues of all wagons or other vehicles.

A further object of this invention is to provide a mounting for the evener bar upon 25 the tongue which will reduce the friction between the evener bar and the tongue as much as possible and which will absolutely release the evener bar from its engagement with the tongue when the detaching device 30 is operated.

A further object is to provide a device of this character in which there are practically no projections which will be liable to engage the evener bar and prevent or impede its release from the tongue.

Other objects will appear in the course of the following description.

The invention is illustrated in the accompanying drawings, wherein:

40 Figure 1 is a side elevation of a tongue with my detaching device applied thereto, the evener bar being in section;

Fig. 2 is a top plan view of the construction shown in Fig. 1;

45 Fig. 3 is a perspective view of the plate 19;

Fig. 4 is a vertical section through the evener bar and the plates 16 and 19.

Referring to these drawings, 10 designates a tongue of any usual or suitable construction, and 11 any suitable or usual yoke. Mounted upon the upper face of the tongue is a plate 12 which is fastened to the tongue in any suitable manner at the base thereof, as by means of bolts or rivets 13, this plate 55 being formed to provide a hinge bead 14. Hinged to this hinge bead by means of the

pintle 15 is a metallic strip 16 which is upwardly bowed or bent and which is formed intermediate of its ends with a concavo-convex socket 17 and at its extremity with 60 a perforation 18. Attached to the upper face of the tongue forward of the plate 12 is a plate 19 which at its middle is enlarged as at 20 and at the center of this enlargement the plate is depressed so as to form 65 a socket 21 disposed ordinarily exactly opposite the socket 17 formed in the strip 16. This plate 19 is attached to the tongue in any suitable manner, as by bolts or rivets, and at its forward end has the lateral up- 70 wardly extending flanges 22 each of which is notched as at 23, these flanges being beveled toward their rear end somewhat.

The plate 19 at its forward end is also provided with the upwardly projecting stud 75 24 adapted to be inserted through the opening 18 in the strip 16. For the purpose of locking the strip 16 into operative engagement with the plate 19 and preventing the detachment of the stud 24 from the perforation 18, I mount upon the under side of the tongue the approximately U-shaped resilient member 25 which is bent to form a base resting against the tongue, then extends downward in a curve and then rearward to form the resilient leaf 26. The extremity of this leaf is bent to form a bead 27. Attached to this bead by means of a transverse pintle 28 is an eccentric clip 29 having an integral rigidly connected handle portion 30 which normally extends forward from the clip and downward. The side bars of the clip 29 are provided with the outwardly projecting studs 31 which engage 80 with eyes formed in the extremity of a U- shaped bail or locking member 32 which extends upward and over the strip 16 and the plate 19 and which is normally disposed in the notches 23. It will be seen that when the eccentrically mounted clip 29 is in the 85 position shown in Fig. 1, the spring 25 will exert a downward tension upon the U-shaped bail 32 which will hold it in place within the notches 23 and that when in place in these notches this bail will prevent 90 the detachment of the strip 16 from its engagement with the stud 24.

Attached to the tongue, on opposite sides thereof, are the springs 33 which springs are connected to the downwardly extending legs 110 of the U-shaped bail or locking member. When this locking member is in engagement

with the notches 23 these springs 33 are under tension. Attached to the under face of the tongue, and, as illustrated, disposed between the base of the spring 25 and the 5 tongue, is a guard 34 composed of a strip of metal which extends forward and downward to a point below the handle 30 of the eccentric clip. The spring and this guard 34 may be attached to the tongue by means 10 of a bolt 35 passing up through the spring and guard and through the plate 19.

The evener bar, which is designated 36, as 15 illustrated in Fig. 4, is formed upon its upper and lower face with spherical or hemispherical pivot studs 36 which, as illustrated, are cast or otherwise formed in one piece with base plates 37 attached to the evener bar, these spherical or hemispherical studs fitting within the sockets 17 and 21, 20 respectively, so that the evener bar has free oscillatory movement as upon a pivot.

Attached to the extremity of the handle member 30 of the eccentric clip 29 is a rod 38 which, however, may be in the form of 25 a flexible connection, this rod extending rearward and being connected to a flexible connection 39 passing upward over a suitable pulley or other support disposed at the front of the wagon. This flexible connection 30 may pass up through the dashboard or through the bottom of the wagon and may be connected to a lever either at the front or rear of the wagon. I do not wish to be limited to any particular manner of mounting 35 this operative connection consisting of the members 38 and 39 as this will vary with different types of vehicles, and whiffle trees are of course to be connected to the evener bar 35. Ordinarily the evener bar will be 40 held in pivoted position upon the tongue by the engagement in the sockets 17 and 21, the strip 16 being held in operative position by means of the U-shaped locking member 32. Now in case the draft animals run 45 away or it is desired to detach them from the tongue for any other reason, it is only necessary to pull upon the connection 38 which will draw downward and rearward upon the member 30, thus, after the eccentric clip 29 has turned upon its center, releasing 50 the locking member 32 and permitting the springs 33 to draw the upper end of the locking member forward. This entirely releases the locking strip 16 and the 55 pull of the draft animals upon the evener bar pulls it out of the sockets 17 and 21 and frees it entirely from engagement with the tongue. Inasmuch as the forward end of the tongue is simply inserted through an 60 opening in the neck yoke, it is obvious that the animals will be completely released from the vehicle and that the vehicle will come to a stop.

While my advice is particularly adapted 65 to poles or tongues, it is obvious that like

means may be used in connection with the cross bar of a pair of shafts and the whiffle tree be released from this cross bar by the same means illustrated. Of course under these circumstances provision must be made 70 for releasing the holdback straps from engagement with the shafts so that the forward movement of the draft animal will detach it from the shafts.

While I have illustrated certain details of 75 construction which I have found to be very effective in practice, I do not wish to be limited to these as it is obvious that many changes in these details might be made without departing from the spirit of the invention. The ball and socket joint formed by the engagement of the members 36^a in the sockets 17 and 21 affords a free movement for the evener bar and at the same time permits a ready detachment of the evener bar 85 from its engagement with the irons 16 and 19 as soon as the wheel 16 is released. This is of course very important inasmuch as any impediment to the complete release of the evener bar would tend to prevent proper 90 action of the mechanism.

It is obvious that this device may be attached to tongues already constructed with only the necessity of drilling holes for the proper bolts or rivets whereby to hold the 95 plates 12 and 19 to the upper face of the tongue. It is also obvious that it may be attached to various forms of tongues without material change.

Having described the invention, what I 100 claim is:

1. The combination with a tongue, of a plate attached to the upper face of the tongue and formed with a concave socket at its middle and with upwardly extending flanges at its forward end and with an upwardly extending stud between said flanges, a member hingedly connected at its rear end to the tongue, arching over said plate and formed with a concave socket in alinement with the socket in the plate and also formed with a perforation for the reception of said stud, an evener bar having spherical trunnions normally disposed in said sockets, a U-shaped locking member, an eccentrically pivoted member operatively mounted upon the under face of the tongue and connected to said U-shaped locking member and having an operating extension, said eccentric when turned into one position drawing the locking member downward to thereby hold the perforated extremity of the hinge member in engagement with the stud, and manually operable means for rotating said eccentric to raise said locking member to 115 thereby free the hinge member and the evener bar.

2. In a horse detaching device the combination with a tongue, a plate disposed upon the upper face of the tongue and having a 130

concave socket and having upwardly extending lateral flanges at its forward end and an upwardly extending stud between the flanges, the flanges being notched, a 5 member hinged at its rear end to the tongue and arching over said plate and being formed intermediate its ends with a socket corresponding to the socket in the plate and at its free end with a perforation for the 10 said stud, an evener bar having spherical trunnions normally disposed in said socket, a U-shaped spring mounted upon the under face of the tongue, a clip pivotally mounted upon said spring and having studs projecting 15 laterally from it and eccentric to its pivotal axis, said clip having a handle portion, a U-shaped bail having its ends connected to said studs on the clip and normally disposed in the notches of said flanges, springs 20 urging the U-shaped bail toward the forward end of the tongue, and means attached to said handle portion of the clip whereby it may be rotated against the force of the first-named spring to lift the yoke and 25 thereby release the hinge member.

3. The combination with a tongue, of a plate attached to the upper face of the tongue and having an upwardly extending stud at its forward end, a member hingedly connected at its rear end to the tongue, arching over said plate and formed with a 30 perforation for the reception of the stud, an evener bar, the evener bar and the stud plates being formed with coacting sockets and spheroidal trunnions, a U-shaped locking member embracing the tongue and arching over the forward end of the hinged member and the forward end of the plate, a 35 spring urging the U-shaped locking member forward, means disposed below the 40

tongue for drawing the locking member downward to thereby hold the hinged member in engagement with the stud, and manually operable means for releasing said locking means to thereby free the hinged member and permit the evener bar to be withdrawn. 45

4. The combination with a tongue, of a plate attached to the upper face of the tongue, a member hingedly connected at its rear end to the tongue and arching over 50 said plate, the hinged member and the plate being formed one with a stud and the other with a perforation engaging the stud, an evener bar disposed between the hinged member and the plate, the hinged member and said plate and the evener bar being formed with coacting sockets and trunnions, a U-shaped locking member embracing the 55 tongue and normally extending over the free end of the hinged member, a U-shaped spring mounted upon the under face of the tongue, an eccentric mounted upon the end of the spring and to which the locking member is pivotally connected, said eccentric having a forwardly and downwardly projecting arm, a spring connected to the upper end of the locking member to urge it forward when it is released from its locking 60 engagement, and means engaging the arm on the eccentric for manually releasing said eccentric to thereby permit it to be shifted upward by the first named spring and forward by the second named spring. 65

In testimony whereof I hereunto affix my signature in the presence of two witnesses.
